(57) CLAIM

The ornamental design for a portable sink with foldable faucet, as shown and described.

DESCRIPTION

FIG. 1 is a front and left side perspective view of a portable sink with foldable faucet showing our new design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof;

FIG. 7 is a bottom plan view thereof;

FIG. 8 is a front and left side perspective view thereof showing the faucet folded;

FIG. 9 is a top plan view thereof showing the sink covered; and,

FIG. 10 is a front and left side perspective view thereof showing the faucet and shelf folded.
